3,813,000 A	5/1974	Underwood
3,828,999 A	8/1974	Humphrey
3,872,994 A	* 3/1975	Hyde
3,915,296 A	10/1975	Spencer
3,927,790 A	* 12/1975	Chase et al.
3,952,911 A	4/1976	Bozek et al.
4,051,265 A	9/1977	Kirschenbaum et al.

FIG. 2 is a top perspective view of the snack food container
of the present invention;FIG. 3 is a front elevation view of the snack food container
of the present invention, with the rear elevation view a
mirror image of the front elevation view;FIG. 4 is a right elevation view of the snack food container
of the present invention, with the left elevation view a mirror
image of the right elevation view;FIG. 5 is a top plan view of the snack food container of the
present invention; and,FIG. 6 is a bottom plan view of the snack food container of
the present invention.The broken lines defining a center portion of the snack food
container, as shown in FIGS. 1, 2, 3, and 4, are for illustrative
purposes only and form no part of the claimed design.**1 Claim, 3 Drawing Sheets****U.S. PATENT DOCUMENTS**
